APPARATUS FOR SPRAY DRYING

William Spencer Bowen, Westfield, N. J.

Application November 20, 1934, Serial No. 753,857

13 Claims. (Cl. 159—4)

The invention embodies improved apparatus and processes for carrying out operations by means of which substances may be treated in such fashion as to be effectively homogenized or spray dried.

5 An object of the invention is to provide an improved process and apparatus wherein a rotating fluid wall is maintained within the drying chamber inwardly of the periphery thereof in such fashion as to avoid the accumulation of products 10 upon the walls of the chamber.

15 A further object of the invention, accordingly, is to provide a method and apparatus by means of which fluids may be treated by an improved recirculating system including the provision of a rotating air curtain or wall formed by a recirculated fluid. In this connection, it is to be noted that the system contemplates the substantial drying 20 of products sprayed into the drying chamber prior to contact thereof with the recirculated fluid which is directed into the drying chamber in the form of a curtain or rotating fluid wall, this being effected by spacing the rotating curtain or wall from the spraying mechanism.

25 A further object of the invention is to provide an improved drying mechanism by means of which a medium may be recirculated to form an effective rotating wall or curtain adjacent the interior surface of the drying chamber and spaced 30 from the spraying mechanism. In this connection, the drying device is preferably formed with a manifold and vertical nozzles which are properly oriented in spaced relationship about the walls of the chamber.

35 A further object of the invention is to provide an apparatus and process by means of which complete recovery of all dried particles is effected prior to the final exhaust of the fluid in which the particles are suspended, the heat values in the last 40 named fluid being substantially removed therefrom to effect preheating and carbonating of the substance to be treated.

45 Further objects, not specifically enumerated above, will be apparent as the invention is described in greater detail in connection with the accompanying drawing, wherein:

Figure 1 is an enlarged view in section of the drying mechanism taken on the broken line 3—3 of Figure 2, and looking in the direction of the 50 arrows.

Figure 2 is a horizontal view in section, taken on the line 4—4 of Figure 1, and looking in the direction of the arrows.

55 Figure 3 is a detail view showing the structure of the spray head shown in Figure 1.

With reference to Figure 1, the apparatus will be seen to include a drying mechanism indicated at 10 with which a fan 11 is associated to facilitate the flow of a medium therethrough. A conduit 12 provides communication between an exhaust manifold 13 of the drying mechanism and the suction side of the fan. From the fan 11, fluid with particles in suspension is directed through a pipe 14 to one or more dust collectors 15 which may be of any well known design. The solid particles recovered from the collectors 15 may be directed to receiving mechanism, not shown, and a portion of the exhaust from the collectors may be returned to the drying chamber through a pipe line 17.

With reference to Figures 1 and 2, the substance 15 to be dried is introduced into the drying chamber from the pipe line 40 by means of a spray head 47. The spray head 47 may be formed as shown in Figure 3 wherein the pipe 40 communicates with the interior of the head 47 and is directed downwardly through the chamber 48 thereof. In chamber 48 is received a valve stem 49 about which a suitable screw or thread 50 is formed in order that the fluid may be subjected to a whirling motion prior to being discharged from the spray head. The lower portion of the stem 49 carries a valve plate 51 which is adapted to be moved against a valve seat 52 formed upon the bottom of the head 47. The position of the valve plate 51 with respect to the seat 52 may be varied by means of a nut 53, or other suitable means by which the stem may be turned in its thread 54.

55 A drying medium is directed through a pipe 56 into a discharge member 57 centrally of the drying chamber 10. The discharge member is formed with a converging outlet 58 which is positioned about the spray head 47 in order that the drying medium may be directed downwardly against the spray of substance discharged from the head. The drying chamber is formed with an outlet manifold 13 above referred to which is positioned substantially flush with the floor 59 of the drying chamber. Apertures 60 are formed in the walls of the drying chamber in order that the outlet manifold 13 may communicate therewith.

40 In order that a portion of the exhaust from the drying mechanism may be recirculated therethrough, the fan 11 is provided with a second outlet communicating with a pipe 61. Pipe 61 50 communicates with an upper manifold 62 about the exterior of the drying chamber, the manifold being formed with downwardly extending chambers 63 which may terminate adjacent the outlet manifold 13. Each chamber 63 is formed with 55

an elongated nozzle 64 which directs fluid therefrom at an angle with respect to the radius of the drying chamber. In the form shown the nozzle 64 directs fluid therefrom at an angle of substantially 45° with respect to radii of the drying chamber as indicated by the dot and dash arrows in Figure 2. A series of horizontal rectifying plates 65 is provided in each of the nozzles 64 in order that the flow of fluid discharged from the nozzle may be in horizontal planes. In this fashion, the vertical nozzles 64 form a rotating curtain or wall of fluid which is spaced from the spray head 47 and thus serves to pick up the substance in the chamber and subject it to an effective drying and treating operation.

If desired, the drying chamber may be provided with a rotatable hollow sweeper 66, receiving a portion of the discharge from the collectors 15 through pipe 47. The construction of this sweeper may be in accordance with the structure shown in my Patent No. 1,946,566.

I claim as my invention:

1. A drying mechanism comprising a chamber forming means, means at the top of the chamber and adjacent the axis thereof to introduce a substance to be dried, means to introduce a drying medium into the chamber adjacent the last named means, means to remove the substance and medium from adjacent the bottom of the container, and means to introduce a plurality of fluid streams into the chamber at the side thereof at angles to radii from the axis of the chamber and to tangents to said radii to form a rotating fluid wall therein.

35 2. A drying mechanism comprising a chamber forming means, means at the top of the chamber and adjacent the axis thereof to introduce a substance to be dried, means to introduce a drying medium into the chamber adjacent the last named means, means to remove the substance and medium from adjacent the bottom of the chamber, and elongated vertically disposed nozzles in the sides of the chamber disposed at angles to radii from the axis of the chamber and to tangents to said radii to introduce a plurality of fluid streams into the chamber to form a rotating fluid wall therein.

3. A drying mechanism comprising a chamber forming means, means at the top of the chamber and adjacent the axis thereof to introduce a substance to be dried, means to introduce a drying medium into the chamber adjacent the last named means, means to remove the substance and medium from adjacent the bottom of the chamber, elongated vertically disposed nozzles in the sides of the chamber disposed at angles to radii from the axis of the chamber and to tangents to said radii to introduce a plurality of fluid streams into the chamber to form a rotating fluid wall therein, and plates in the nozzles to cause the fluid of the fluid streams to be directed in a path lying in a plane perpendicular to the axis of the chamber.

4. A drying mechanism comprising a chamber forming means, means at the top of the chamber and adjacent the axis thereof to introduce a substance to be dried, means to introduce a drying medium into the chamber adjacent the last named means, means to remove the substance and medium from adjacent the bottom of the chamber, elongated vertically disposed nozzles in the sides of the chamber disposed at angles to radii from the axis of the chamber and to tangents to said radii to introduce a plurality of fluid streams into the chamber to form a rotating fluid wall

therein, and means to direct removed dried substance and medium to the nozzles.

5. A drying mechanism comprising a chamber forming means, means at the top of the chamber and adjacent the axis thereof to introduce a substance to be dried, means to introduce a drying medium into the chamber adjacent the last named means, means to remove the substance and medium from adjacent the bottom of the chamber, elongated vertically disposed nozzles in the sides of the chamber disposed at angles to radii from the axis of the chamber and to tangents to said radii to introduce a plurality of fluid streams into the chamber to form a rotating fluid wall therein, a manifold adjacent the top of the chamber communicating with the nozzles, and means to direct removed dried substance and medium to the nozzles.

6. The process of spray drying comprising introducing a substance to be dried into a chamber with a drying medium with a whirling motion, removing the dried substance and medium and forming a fluid wall of a portion of the dried substance and medium adjacent the wall of the chamber moving in the direction of whirl of the substance to be dried.

7. The process of spray drying comprising introducing a substance to be dried into a chamber in an outwardly directed whirling spray with a drying medium which flows downwardly against the spray, removing the dried substance and medium, and injecting a plurality of streams of the dried substance and medium at angles to radii extending from the axis of the chamber and to tangents to said radii to form a rotating wall thereof adjacent the chamber wall but spaced therefrom.

8. A drying mechanism comprising a chamber forming means, means at the top of the chamber and adjacent the axis thereof to introduce a substance to be dried into the chamber with a whirling motion about the axis of the chamber, means to remove the substance and medium from adjacent the bottom of the chamber, and means to introduce a fluid into the chamber at the side thereof at an angle to a tangent to the chamber at a point at which the last named fluid is introduced and in the direction of whirl of the substance to be dried, whereby a rotating curtain of fluid is provided between the chamber wall and the axis of the chamber which rotates in the direction of the whirl of the substance to be dried.

9. A drying mechanism comprising a chamber forming means, means at the top of the chamber and adjacent the axis thereof to introduce a substance to be dried into the chamber with a whirling motion about the axis of the chamber, means to introduce a drying medium into the chamber adjacent the last named means, means to remove the substance and medium from adjacent the bottom of the chamber, and means to introduce a fluid into the chamber at the side thereof at an angle to a tangent to the chamber at the point at which the last named fluid is introduced and in the direction of whirl of the substance to be dried, whereby a rotating curtain of fluid is provided between the chamber wall and the axis of the chamber which rotates in the direction of whirl of the substance to be dried.

10. A drying mechanism comprising a chamber forming means, means at the top of the chamber and adjacent the axis thereof to introduce a substance to be dried into the chamber with a whirling motion about the axis of the chamber, means to remove the substance and medium from

adjacent the bottom of the chamber, and means to introduce a fluid into the chamber at the side thereof at an angle to a tangent to the chamber at the point at which the last named fluid is introduced and in the direction of whirl of the substance to be dried, the angularity of the direction of motion of the last named fluid being such as to form a rotating curtain of fluid spaced from the chamber wall and whirling in the direction of whirl of the substance to be dried.

11. A drying mechanism comprising a chamber forming means, means at the top of the chamber and adjacent the axis thereof to introduce a substance to be dried into the chamber with a whirling motion about the axis of the chamber, means to remove the substance and medium from adjacent the bottom of the chamber, and means extending axially of the chamber to introduce a fluid into the chamber at the side thereof at an angle to a tangent to the chamber at the point at which the last named fluid is introduced and in the direction of whirl of the substance to be dried, the angularity of the direction of motion of the last named fluid being such as to form a rotating curtain of fluid

spaced from the chamber wall and whirling in the direction of whirl of the substance to be dried.

12. The process of spray drying comprising introducing a substance to be dried into a chamber, introducing a drying medium therein with a whirling motion, removing the dried substance and medium, and forming a fluid wall of a portion of the dried substance and medium adjacent the wall of the chamber moving in the direction of whirl of the substance to be dried.

13. A drying mechanism comprising a chamber forming means, means to remove a substance to be dried and a treating medium from adjacent the bottom of the chamber forming means, means to introduce a plurality of fluid streams of a treating medium into the chamber forming means at the sides thereof at angles to radii from the axis of the chamber forming means and to tangents to said radii to form a rotating fluid wall therein, and means to introduce a substance to be dried into the chamber forming means inwardly of the rotating fluid wall.
